UNITED STATES PATENT OFFICE.

VINCENT WILLIAM JOSEPH SMITH, OF EDINBURGH, SCOTLAND.

AUTOMATIC COUPLING FOR RAILWAY-CARRIAGES, WAGONS, AND THE LIKE.

1,073,535.

Specification of Letters Patent. Patented Sept. 16, 1913.

Application filed April 16, 1913. Serial No. 761,484.

To all whom it may concern:

Be it known that I, VINCENT WILLIAM JOSEPH SMITH, a subject of the King of the United Kingdom of Great Britain and Ireland, and resident of Fernsicht, Belgrave Road, Corstorphine, Edinburgh, Scotland, mechanic, have invented certain new and useful Improvements in Automatic Couplings for Railway-Carriages, Wagons, and the like, of which the following is a specification.

This invention relates to an improved automatic coupling for railway carriages, wagons and the like of the type having means for securing a link or shackle in the proper position to engage a swinging hook member and for retaining the hook member in the coupled position and means for releasing same, and this invention has for its object to improve the construction of such automatic couplings.

Figure 1 is an elevation of the coupling, showing the coupling in the coupled position, one half being in section and one half in elevation. Fig. 2 a plan view of Fig. 1, also partly in section.

Referring to the drawing, I construct the body of the coupling in the form of a box like casting or forging A having two projecting side plates or cheeks a formed with downwardly projecting horns a¹. The said box like portion is pivotally connected to the draw-bar B of the vehicle by the pin b and nut b¹ and it has formed on it, above their hereinbefore mentioned horns a¹ a pair of horizontally projecting arms or slotted plate portions a². In the space between the two projecting side plates or horned cheeks a, I provide a pivoted hook member C which is capable of swinging in a vertical plane on the pin c, the said hook having formed on it a projecting tail c¹ having the stoppers c² formed on it, the said stoppers engaging with the recess a³ formed in the side plates or cheeks a. The stoppers c² and recesses a³ are for the purpose of preventing the hook C from being lifted above the horizontal position shown on the left hand of Fig. 1. On the outside of the hereinbefore described box like member A I provide a shackle or link D which is pivotally attached to the box like casting by means of the pin d and secured thereto by collars d¹ or by other suitable means such as nuts or the like, the said link D also being provided at the eye end

where it is attached to the coupling body with a pair of snugs or tails d².

On the top of and at right angles to the coupling, I provide a horizontal spindle or axle E which carries three downwardly projecting fingers or catches, two of them—c—being on the outsides of the cheek plates a of the coupling for the purpose of engaging with the snugs or tails d² on the link D and maintaining the said link in a horizontal position when desired. The middle one c¹ of the three fingers is placed between the cheek plates a for the purpose of engaging with the tail c¹ of the pivoted hook C and maintaining the said hook in a horizontal position so as to engage with the link D of the coupling on the next vehicle. The cross spindle E is also provided with a weighted lever e² or the like for the purpose of releasing the hook portion C when it is desired to uncouple the vehicles.

The action of the coupling is as follows: Suppose that it is desired to couple two vehicles together; the link D of one of the couplings is lifted up to a horizontal position and the outside depending fingers or catches c actuated by the hereinbefore mentioned weighted lever e² engage with the snugs or tails d² of the link and hold it in a horizontal position as in the right hand half of Fig. 1. The vehicles now being brought together, the projecting link portion D of the one coupling enters the space between the horned side cheeks a¹ and top plate or member a² of the other coupling—guided by the said horns—and comes into contact with the tail c¹ of the pivoted hook C—which is in the position shown by the chain lines in the left hand half of Fig. 1 and forces it backward and so lifts the hook C up into a horizontal position, thereby causing it to engage with the link D as shown in Fig. 1. The middle depending finger or catch c¹ of the cross spindle E then comes into engagement with the tail c¹ of the hook member C and retains the said hook in engagement with the link of the other coupling thereby securely coupling the vehicles together as shown in Fig. 1. To uncouple the vehicles it is only necessary to lift up the weighted lever e² and thereby trip the depending finger c¹ clear of the tail c¹ of the hook and so allow it to fall clear of the link or the other coupling.

I may construct the couplings of any suit-

able materials such as cast steel, malleable iron, or it may be made from forgings.

With reference to the releasing gear of the couplings I may provide the means shown 5 in Figs. 3, 4, 5 and 6.

For shunting purposes when the vehicles do not require to be coupled, the depending fingers or catches e are simply disengaged from the snugs or tails d^2 on the end 10 of the link, by raising the weighted lever e^2 .

Claims:

1. An automatic car coupling comprising a main body pivotally connected with the draw-bar of the car, said body having forwardly projecting cheeks and a similarly projecting top plate, a coupling link journaled to said cheeks a coupling hook hinged between said cheeks; an arresting bolt journaled in said body, arresting fingers on said bolt adapted to engage with said link and said hook respectively to retain them in horizontal position; a counter poised lever on said bolt tending to swing said fingers forward; said link when in horizontal position adapted to impinge with the hook in a similarly arranged coupling on another car, when said hook hangs in the vertical position, thereby throwing the hook into horizontal position and into engagement with a finger of its arresting bolt and with said coupling link.

2. An automatic car coupling comprising a main body pivotally connected with the draw-bar of the car permitting horizontal

oscillation of said body, said body having forwardly projecting cheeks and a similarly projecting top plate above said cheeks, a coupling link journaled to said cheeks and provided with a rearward projection; a coupling hook hinged between said cheeks, 40 in front of the pivot point of said link, said hook and said link adapted to swing in a vertical direction; said hook being provided with a tail piece having transversely extending lugs adapted to contact 45 with said cheeks to limit the swinging of said hook; an arresting bolt horizontally journaled in said body, arresting fingers on said bolt adapted to engage with said link projection and said hook tail respectively, 50 and retain the link and the hook in horizontal position; a counter poised lever on said bolt tending to swing said fingers forward, said lever, on being manually operated causing the disengagement of said fingers from said hook and link; said link when in horizontal position adapted to impinge with the tail of the hook in a similarly arranged coupling on another car, when said hook hangs in the vertical position, thereby throwing the hook into horizontal position and into engagement with a finger of its arresting bolt and with said coupling link.

VINCENT WILLIAM JOSEPH SMITH.
